HAIR WAVING APPLICATOR

Frank Foriyes, Brooklyn, N. Y.

Application June 27, 1933. Serial No. 677,787

8 Claims. (Cl. 132—36.2)

The invention relates to a hair waving applicator adapted for utilization in the setting of waves in hair. More particularly it relates to an absorbent applicator for use in setting a wave of a permanent nature in hair, and includes correlated discoveries and improvements whereby the imparting of a wavy condition to hair is enhanced.

An object of the invention is to provide an applicator of the above type which may be easily wrapped about the hair, and which while adhering to the hair closely enough to carry out its function effectively can be readily removed.

A further object of the invention is the provision of an applicator which may be utilized with ease for the waving of hair, particularly a permanent waving, and which can be readily, efficiently and economically manufactured on a commercial scale from inexpensive and generally available materials.

An additional object of the invention is the provision of an applicator adapted to replenish the hair treating composition, and to aid in the treatment of the hair.

Other objects of the invention will in part be obvious and will in part appear hereinafter.

The invention accordingly comprises an article of manufacture possessing the features, properties, and the relation of elements which will be exemplified in the article hereinafter described and the scope of the application of which will be indicated in the claims.

In the practice of hair waving, which is to be of a permanent nature, the hair is divided into a plurality of strands, the size of the strands depending on the thickness or fineness of the hair and upon the kind of wave desired. Each strand is wound upon a curler, usually a thin metallic rod. The strand when so wound is tied at each end, and then subjected to a hair treating composition under the influence of heat.

The present invention contemplates an applicator including, in combination, elements coacting to subject a strand of hair so wound upon a curler with a hair treating composition and to protect the hair from any damaging effects of heat while at the same time acting as a heat conductor.

Described generally, this is effected by means of a hair waving applicator consisting, in combination, of two parts successively wrapped about the hair. One part consists of a pad portion, which may be moistened with a hair treating composition and securely wrapped about the hair.

This part may consist of an inner absorbent mem-

ber and an outer strengthening member. The second part, which upon further rolling of the applicator about the hair encases the pad portion, comprises a heat conductor and an absorbent material, enclosed in a protective means.

For a fuller understanding of the nature and objects of the invention, reference should be had to the following detailed description taken in connection with the accompanying drawing, in which:

Figure 1 is a plan view of the appliance embodying features of the invention, sections being broken away to show the various elements.

Referring more particularly to the drawing, there is shown the applicator 1, which is of the general configuration and size illustrated in Fig. 1. The applicator may be considered as being divided into two sections. One section 2 contains an absorbent material and a heat conductor enclosed in a protective means, and the other section 3 is a pad portion.

Referring again to the pad portion 3, reference numeral 10 indicates an inner absorbent member, for example a flexible porous textile material. This member 10 is enclosed in a relatively coarse meshed material, for example cheese cloth or cloth of a similar nature, which acts as a protective and strengthening member. This is shown by reference numerals 9 and 11. 11 indicates that part which is in direct contact with the hair when rolling, and 9 indicates the outer part of the pad portion. If desired, the fire hazard may be lowered by treating the protective and strengthening material with a fire-proofing material, for example a solution of ammonium sulphate or other ammonium salt.

The inner absorbent member 10 and the outer strengthening members 9 and 11 may be held together by any suitable means, the preferred means being that shown in the drawing, namely rows of stitching, each indicated by reference numeral 12.

In the part of the applicator indicated by reference numeral 2, 6 is an absorbent material, which may be an extended portion of the absorbent member 10 or separate therefrom and composed of a suitable absorbent which may be the same material as the member 10. This absorbent material 6 may be impregnated or coated with an oleaginous substance. The oleaginous substance which may be utilized includes nondrying oils, particularly the vegetable oils such as castor oil, corn oil, cotton seed oil, rape seed oil, olive oil and peanut oil.

In close contact with the material 6 is a heat

conductor 5, which may consist of a thin sheet of metal, as for example a foil of tin or aluminum. This acts as an impervious heat conductor and prevents the escape of vapors and steam evolved by the application of heat to the hair treating composition. Such vapors and steam are essential factors in imparting a wavy condition to the hair.

The absorbent material 6 and the heat conductor 5 are enclosed in a protective means, for example a cellulosic material such as parchment-paper, waxed-paper, cellophane, etc., the outer portion, when rolled, bearing the reference numeral 4 and the inner portion bearing the reference numeral 7. The portion 7 is perforated, the numeral 8 indicating the perforations. These perforations allow vapors arising from the oleaginous material under the influence of heat to pass through and thereby the oleaginous material contained in the hair treating composition is replenished and the treatment of the hair abetted.

The applicator herein described may be used as follows: The pad portion 3 is moistened with a hair treating composition, for example, such as that described in my copending application Serial No. 670,216, filed May 9, 1933.

The strands of hair wound on the curler are then securely wrapped in the pad portion beginning at the edge 13. The hair is thus covered with the pad portion and further wrapping envelops the pad with the heat conducting portion of the applicator. The rolled hair is then surrounded by a heating medium and subjected to heat.

In operation the heat conducted to the pad portion moistened with a hair treating composition causes the latter to evolve steam and vapors which impart to the hair a wave which is of a permanent nature. During this treatment the heat likewise causes the oleaginous material contained in the absorbent material enclosed in the protective means to give off vapors which act in the manner above set forth. It will thus be seen that there has been disclosed a hair waving applicator which is of marked utility in imparting to hair a wave of a permanent nature.

Since certain changes may be made in the above composition of matter and different embodiments of the invention could be made without departing from its scope, it is intended that all matter contained in the above description shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. As an article of manufacture, a hair waving applicator, comprising in combination a pad portion, and an absorbent material and a heat conductor enclosed in a protective means.

2. As an article of manufacture, a hair waving applicator, comprising in combination a pad portion, and an absorbent material and a heat conductor enclosed in a perforated cellulosic material.

3. As an article of manufacture, a hair waving applicator, comprising in combination a pad portion, and an absorbent material and a metallic heat conductor enclosed in a protective means.

4. As an article of manufacture, a hair waving applicator, comprising in combination a pad portion, and an absorbent material impregnated with an oleaginous substance and a heat conductor enclosed in a protective means.

5. As an article of manufacture, a hair waving applicator, comprising in combination a pad portion consisting of an inner absorbent and an outer strengthening member, and an absorbent material and a heat conductor enclosed in a protective means.

6. As an article of manufacture, a hair waving applicator, comprising in combination a pad portion consisting of an inner absorbent and an outer strengthening member, said members being securely attached one to the other and an absorbent material which is an extension of the absorbent member of said pad portion and a heat conductor enclosed in a protective means.

7. As an article of manufacture, a hair waving applicator, comprising in combination a pad portion consisting of an inner absorbent and an outer strengthening member, and a absorbent material impregnated with an oleaginous substance and a metallic heat conductor enclosed in a perforated cellulosic material.

8. As an article of manufacture, a hair waving applicator, comprising in combination a pad portion, and a heat conductor enclosed in a protective means.

FRANK FORIYES.
